[57] CLAIM

The ornamental design for a wall-mounted lighting control panel, as shown and described.

DESCRIPTION

FIG. 1 is a front elevational view of a wall-mounted lighting control panel showing our new design;

FIG. 2 is a right side elevational view thereof, the left side being a mirror image of that shown;

FIG. 3 is a bottom plan view thereof;

FIG. 4 is a top plan view thereof;

FIG. 5 is a top, front, and left side perspective view thereof, with the hinged cover shown in an open position; and

FIG. 6 is an enlarged front elevational view thereof, with the hinged cover shown in an open position.

The broken-line depiction of a portion of the housing shown in the views is for illustrative purposes only and forms no part of claimed design.
